DESIGN FOR A PIPE

Frank Furedy and Marvin William Dynes, Chicago, Ill., assignors to Sun-Kraft, Inc., Chicago, Ill., a corporation of Delaware

Application February 8, 1947, Serial No. 136,776

Term of patent 14 years

(Cl. D85—8)

To all whom it may concern:

Be it known that we, Frank Furedy and Marvin William Dynes, citizens of the United States, residing in Chicago, Cook County, State of Illinois, have invented a new, original, and ornamental Design for a Pipe, of which the following is a specification, reference being had to the accompanying drawing, forming a part thereof.

Fig. 1 is a side elevational view of a pipe showing our new design;

Fig. 2 is a top plan view of the pipe;

Fig. 3 is a bottom plan view of the pipe; and

Fig. 4 is an end view of the pipe.

We claim:

The ornamental design for a pipe, substantially as shown.

FRANK FUREDY.
MARVIN WILLIAM DYNES.
